Patented May 20, 1919.

FIG. 1

FIG. 2

FIG. 3.

INVENTOR:
REGINALD F. PECKHAM,
BY *Albert Davis*
His ATTORNEY.

UNITED STATES PATENT OFFICE.

REGINALD F. PECKHAM, OF RUGBY, ENGLAND, ASSIGNOR TO GENERAL ELECTRIC COMPANY, A CORPORATION OF NEW YORK.

INDIRECT AND SEMI-INDIRECT FIXTURE.

1,304,363.

Specification of Letters Patent. Patented May 20, 1919.

Application filed March 28, 1917. Serial No. 158,091.

To all whom it may concern:

Be it known that I, REGINALD F. PECKHAM, a subject of the King of Great Britain, residing at Rugby, county of Warwickshire, 5 England, have invented certain new and useful Improvements in Indirect and Semi-Indirect Fixtures, of which the following is a specification.

My invention relates to lighting fixtures 10 and more particularly to fixtures such as are used in systems of semi-indirect and indirect lighting. In such systems the usual practice is to suspend beneath the light source a shallow bowl of translucent or non-trans- 15 parent material, the latter being usually suspended from the ceiling by means of chains, or by means of supports radiating out from a central hanger. The lamp or lamps are suitably supported in this bowl, and the 20 bowl serves to partially or totally re-direct the downward rays of light upwardly onto the ceiling, the latter being white or light colored so as to reflect and diffuse the light rays downward again into the room. Such 25 fixtures, especially where there is only one high candle power lamp with a concentrated source of light supported therein, have the disadvantage that shadows of the suspending chains or radial supports are cast on the 30 ceiling, and also that there is a sharp line of cutoff on the ceiling or the upper part of the wall caused by the opaque bowl in a totally indirect system.

The object of my invention is to overcome 35 these disadvantages and to that end it consists in the employment of a diffusing means of such character and so arranged that the direct rays from the lamp striking the edge of the bowl and the chains are caused to pass 40 through a diffusing medium thereby greatly softening the line of cutoff in non-transparent bowls and diminishing or avoiding the shadows of the chains, while both the indirect and direct rays which do not cause these 45 troubles pass freely upward to the ceiling and are unobstructed and unimpeded by the diffusing means. More particularly I provide bands of diffusing material and arrange them beneath the chains or supports so as to 50 intercept the shadow-casting rays but permit all other rays to freely pass up to the ceiling.

A further object of my invention resides 55 in the arrangement whereby in addition to the avoidance of shadows and sharp outlines

on the ceiling the diffusing means is simply and easily supported and efficient ventilation of the fixture is obtained by the particular arrangement and character of the diffusing means.

Other advantages of my invention will be apparent on an inspection of the drawings accompanying and forming a part of this specification, Figure 1 of which shows one modification of my invention. Fig. 2 shows 65 another modification, and Fig. 3 is a plan view of one element of the fixture illustrated in Fig. 1.

Referring to Fig. 1, there is illustrated an indirect or semi-indirect fixture embodying a bowl 1 suspended by a plurality of chains 2, usually three in number. In an indirect fixture the bowl 1 may be of some opaque material, either metal or glass, and this bowl is conveniently provided with a 70 detachable interior reflector 3, or the interior surface of the bowl 1 itself may comprise a reflecting medium. In a semi-indirect fixture the bowl 1 is preferably of some translucent material, as frosted, opalescent, 75 or prismatic glass, and in this case the interior reflector 3 is dispensed with. In the semi-indirect system a portion of the light passes downwardly from the light source directly through the bowl and a part thereof 80 is reflected up to the ceiling, while in an indirect system all the light is reflected upwardly to the ceiling.

Supported within the bowl is a suitable light source of a concentrated beam, as, for 85 instance, a high efficiency incandescent lamp 4. The rays from this light source 4 often cause objectionable shadows of the chains 2 and sharp outlines of the bowl 1 on the ceiling. In accordance with one feature of my 90 invention, I interpose in the path of the rays which cause this trouble a diffusing medium, while a free and unobstructed passage is offered to all other rays issuing from the light source. This diffusing means consists 95 of diffusing bands located between the suspending chains 2 or radial supports and the light source, and in the preferred arrangement these diffusing bands are incorporated 100 in the clear glass cover or skirt 5 located just above the lamp bulb 4. These bands 6 correspond in number to the suspending chains or radial supports and are incorporated in the skirt 5 in any suitable manner, as by etching, sandblasting or painting in such a 110

manner that they become translucent and diffusing as distinguished from the other parts of the skirt 5 which are transparent and offer a free and unimpeded passage to 5 a great portion of the upward rays. In this manner only the rays which cause shadows are diffused and consequently the efficiency of the unit or fixture is substantially unimpaired, the greater portion of the direct 10 rays passing up to the ceiling without encountering the diffusing medium. The lower edge of the skirt 5 may also be rendered diffusing as shown like the strips or bands 6 in order to obliterate the sharp out- 15 lines of the rim of the bowl 1 upon the ceiling. This skirt 5 may be supported in any suitable manner, as, for instance, by means of downwardly depending fingers 7 coöperating with a ring 8 which is adapted to be 20 slid downwardly over the fingers and cause them to grip the flaring rim of the skirt.

In Fig. 2 is illustrated another modification embodying a translucent or opaque bowl 1 similar to the one illustrated in Fig. 25 1. The diffusing bands in this case are incorporated in a carrier of a character to promote ventilation of the fixture. To this end this carrier consists of a cylindrical member of clear glass 5' resting directly on the bulb- 30 4. Since the carrier or cover does not conform to the configuration of the bulb 4, it may be supported directly thereon without causing undue heating of the bulb at the points of contact, radiation from the bulb 35 being unimpeded thereby. The lower end of the cylinder 5' may be made diffusing, as is indicated in dotted lines, in order to avoid sharp outlines of the bowl on the ceiling.

What I claim as new and desire to secure 40 by Letters Patent of the United States, is,—

1. In indirect and semi-indirect lighting fixtures, the combination of a bowl and a light source therein with a plurality of suspending devices for the bowl attached at one 45 end to the bowl and at the other end to the ceiling support above the light source and a transparent cover for the lamp having bands of diffusing material incorporated therein situated directly between the light source 50 and the suspending devices for intercepting and diffusing the shadow-casting rays, all other rays passing freely to the ceiling without loss by diffusion.

2. In indirect and semi-indirect lighting 55 fixtures, the combination of a bowl and an incandescent lamp therein with a plurality

of suspending devices attached at one end to the bowl and at the other end to the ceiling support above the lamp and a cover of a configuration different from the configuration 60 of the bulb and resting directly thereon, said cover having diffusing means incorporated therein located between the light filament and the suspending devices for intercepting and diffusing the shadow-casting rays.

3. In indirect and semi-indirect lighting fixtures, the combination of a bowl and an incandescent lamp therein with a plurality of suspending devices attached at one end to 70 the bowl and at the other end to the ceiling support above the lamp and a cover resting directly on the bulb, said cover having diffusing means incorporated therein located between the light filament and the suspending 75 devices for intercepting and diffusing the shadow-casting rays.

4. In indirect and semi-indirect lighting fixtures, the combination of a bowl and an incandescent lamp therein with a plurality of suspending devices for the bowl attached at one end to the bowl rim and at the other end to the ceiling support above the incandescent lamp and a transparent cylinder resting on said lamp bulb and having incorporated therein diffusing bands located directly between the light source and the suspending devices for intercepting the shadow-casting rays, all other rays passing freely and unobstructedly to the ceiling.

5. In indirect and semi-indirect lighting fixtures, the combination of a bowl and a light source therein with a plurality of suspending devices attached at one end to the bowl and at the other end to the ceiling support above the light source and a transparent cover for said lamp bulb having incorporated therein diffusing bands situated directly between the light source and the suspending devices and also having incorporated therein a diffusing ring located directly between the rim of the bowl and the light source for intercepting the shadow-casting rays, all other rays passing freely and unobstructedly to the ceiling.

In witness whereof, I have hereunto set my hand this twenty eighth day of February, 1917.

REGINALD F. PECKHAM.
